UNITED STATES PATENT OFFICE.

WILLIAM F. SCHEFFLER, OF CHICAGO, ILLINOIS, ASSIGNOR TO COCHRAN MANUFACTURING & FORGING COMPANY.

DESIGN FOR A COMBINED WRENCH AND SPRING-LEAF OILER.

54,461.

Specification for Design.

Patented Feb. 10, 1920.

Application filed May 19, 1919. Serial No. 298,338. Term of patent 14 years.

To all whom it may concern:

Be it known that I, WILLIAM F. SCHEFFLER, a citizen of the United States, residing in the city of Chicago, county of Cook, and State of Illinois, have invented a new, original, and ornamental Design for a Combined Wrench and Spring-Leaf Oiler, of which the following is a specification, references being had to the accompanying drawing, forming part thereof.

Figure 1 is a plan view, and Fig. 2 a reverse plan view of a combined wrench and spring leaf oiler, showing my new design.

I claim:

The ornamental design for a combined wrench and spring leaf oiler, as shown.

In witness whereof, I have hereunto subscribed my name this 13th day of May, 1919.

WILLIAM F. SCHEFFLER.
